LOOM

Saint Julian Geddings, New Brockland, S. C., assignor of one-fourth to James M. Goff, New Brockland, S. C.

Application October 16, 1937, Serial No. 169,443

3 Claims. (Cl. 139—269)

My invention relates to improvements in weft or filling replenishing looms of the bobbin-changing class.

An important object of the invention is to provide electrically actuated means to shift the latch or dog of the transfeerer to the operative position for engagement with the bunter carried by the lay, when the filling is exhausted from the quill.

10 A further object of the invention is to provide electrical means of the above mentioned character, including contact-feelers, arranged to contact with a metallic sleeve or element mounted upon the quill, when the filling is exhausted, 15 the arrangement of the parts being such that the circuit for effecting the replenishing of the bobbin will not be closed if the shuttle comes to rest beyond defined limits.

20 A further object of the invention is to provide apparatus of the above mentioned character, which is of simple construction, reliable in operation and may be installed upon a conventional loom such as the Draper loom, without materially altering the construction of the same.

25 A further object of the invention is to provide electrically operated contact-feelers, which will cause the apparatus to operate with a high degree of accuracy, eliminating the production of seconds, and the transfer of filled bobbins into 30 the shuttle before the bobbin therein has the filling completely removed therefrom.

35 A further object of the invention is to provide a feeler which will not improperly actuate the transfeerer, by engagement with the filling on the quill and which will not actuate the transfeerer until the filling has its last layer covering the contact element removed from the quill.

40 Other objects and advantages of the invention will be apparent during the course of the following description.

In the accompanying drawings forming a part of this application and in which like numerals are employed to designate like parts throughout the same,

45 Figure 1 is a perspective view of apparatus embodying my invention, showing the same applied to a loom,

Figure 2 is a plan view of the same,

50 Figure 3 is a diagrammatic view showing the electrical circuit and associated elements,

Figure 4 is a transverse section taken on line 4—4 of Figure 2,

55 Figure 5 is a transverse section taken on line 5—5 of Figure 4,

Figure 6 is a plan view of the contact-feeler device, with the top plate removed,

Figure 7 is a side elevation of the filling feeler slide and associated elements, the rock-shafts being in section, taken on line 7—7 of Figure 2, 5

Figure 8 is a central vertical longitudinal section through the filling feeler slide, parts in elevation,

Figure 9 is a transverse section taken on line 9—9 of Figure 7, and, 10

Figure 10 is a side elevation of the transfeerer and associated elements.

In the drawings, wherein for the purpose of illustration is shown a preferred embodiment of my invention, the numeral 10 designates a loom 15 as a whole, which may be a conventional Draper weft-replenishing loom of the bobbin-changing class. The bobbin replenishing means is not shown but is on the end of the loom remote from the end shown in Figure 1 of the drawings. 20 The bobbin replenishing means may be of the type shown in the patent to H. A. Owen, 1,291,101. The numeral 14 is the transfeerer, 15 is the fixed stud upon which the transfeerer is pivotally mounted, and 16 the latch or dog of the transfeerer. The numeral 17 designates the bunter carried by the lay which serves in the forward movement of the lay to engage with said latch or dog 16 when the latter is raised through the action of the weft detecting devices embodying 30 the present invention, so that the bunter may transmit movement through the latch or the dog to the transfeerer to actuate the transfeerer to feed the leading bobbin or other weft carrier into the shuttle. The elements 14, 15, 16 and 17 35 are the identical elements shown and described in Patent 1,291,101. The present invention resides in means to elevate to latch or dog 16, so that it will be engaged by the bunter 17.

The loom comprises a frame including a breast beam 18, and a lay including shuttle boxes 19 (one being shown), for receiving a shuttle 20, detachably holding a quill 21. This quill is of the conventional type except that it is provided with a metal contact band 22, which is approximately one inch in length.

40 Mounted near and above breast beam 18 is my improved filling feeler slide, designated as a whole by the numeral 23. This slide is forked, providing spaced tines 24, receiving therebetween a vertically swinging pawl 25, pivoted to the same at one end, as shown at 26. This pawl is elevated by a retractile coil spring 26', attached thereto, and to a bolt 27, adjustable connected with an inverted U-shaped bridge 28, rigidly secured to 45 50 55

the tines 24. The upward movement of the pawls 25 is limited by an adjustable stop 29, having screw-threaded engagement with an upstanding bracket 30, rigidly carried by one tine 24. An inverted U-shaped lever 31 has a forked end 32, which straddles the bridge 28 and is pivoted thereto at 33, to swing in a vertical plane, and an adjustable bolt 34 is secured to the free end of the lever 31, and is arranged above the pawl 25, 5 to contact therewith, at a point suitably spaced from the pivot 26 of the pawl. The lever 31 is provided with an armature 35, arranged near and above electro-magnets 36, rigidly mounted upon a bracket 37, in turn rigidly secured to the bridge 28. It is thus seen that when the electro-magnets are energized, the lever 31 will move downwardly, and depress the pawl 25, in opposition to its spring 26'. The filling feeler slide 23 is horizontally arranged and partakes of rectilinear reciprocatory movements in a horizontal plane, and one tine 24 has a depending extension 38, slidably supported by the usual filling motion stand 39, it being understood that the slide 23 is substituted for the conventional filling feeler 10 slide. The filling feeler slide 23 has a laterally extending horizontal rib 40, engaged by a stationary bracket 41, which prevents the filling feeler slide 23 moving upwardly and also preventing any tendency for it to move laterally toward the bracket 41, while any lateral movement in the opposite direction would be prevented by the usual straddle bug. However, there is practically no tendency for the slide 23 to partake of lateral displacement. My improved filling feeler 15 slide 23 is provided at one end with an apertured knuckle 42, arranged between apertured knuckles 43, Figure 1, and pivotally connected therewith, as shown at 44. These knuckles are formed upon the upper end of an upstanding vertically swinging lever or starting broad arm 45, which is rigidly mounted upon a rock-shaft 46, in turn suitably mounted upon the frame of the loom and extending to the opposite end of the loom, to actuate the means which raises the dog or latch 16, to 20 be described. This means comprises a crank 47, clamped to the rock-shaft 46, and having a lever 48 clamped thereto, provided with a fork 49, receiving an extension 50 carried by a vertically swinging link 51, pivoted at 52. This link has a slot 53, to receive a pin 54, carried by an extension 55, depending from the dog or latch 16. It is thus seen that the clockwise turning movement of the rock-shaft 46 will elevate the latch or dog 16, as is well known in the art. The rock-shaft is 25 turned in the opposite direction by the usual spring.

The numeral 56 designates a filling cam follower dog or lever, rigidly attached to a coupling 57, in turn rigidly mounted upon a rock-shaft 58, 30 which is cam actuated in the conventional automatic filling replenishing loom. The dog 56 is generally vertically arranged and carries a bolt 59 passing through selected openings 60 in a dog 61. This dog has a depending tail 62, arranged to engage with an adjustable stop bolt 63, carried by the filling cam follower dog or lever 56. By manipulation of the bolts 59 and 63, the dog 61 may be adjusted with respect to the dog 56 and will be securely held in the selected adjusted position without liability of displacement. At its upper end, the dog 61 has a pusher head 64, provided with a tooth 65, to engage with the free end of the pawl 25, when the pawl 25 is lowered. An electrical contact-feeler is provided for coaction 35 with the metallic sleeve 22 to close the circuit and

energize the electro-magnet 36. This feeler comprises a casing 66, rigidly secured to a bracket 67, in turn rigidly secured to the breast beam 18. The casing 66 is formed of insulating material and is made in upper and lower twin casing sections 68. Each casing section is provided with a pair of longitudinal grooves 69, slidably receiving contact-feeler rods 70, made of metal, and provided at their inner ends with lateral extensions 71, arranged to engage shoulders 72, for limiting the outward movement of the feeler rods. The feeler rods are moved outwardly by retractile coil springs 72', having electrical connection therewith and with binding posts 73 and 14. The circuit is made through the springs 72, as will be 10 explained. The contact feeler rods 70 are positioned to be in proper alignment with the contact sleeve 22 of the quill, when the shuttle comes to rest at the proper position in the shuttle box, and when the lay moves toward the contact-feeler rods 70 with a depleted shuttle, these feeler rods 15 electrically engage the sleeve 22, and the sleeve electrically connects the otherwise insulated feeler rods to close the circuit. A wire 75 leading from the positive pole of the source of current is 20 electrically connected with the binding post 73 and a wire 76 is electrically connected with the other binding post 74 and with one end of the winding of one electro-magnet 36, the magnets being connected in series, and a wire 77 is connected with the free end of the winding of the other electro-magnet, and the wire 77 leads to the negative pole of the source of current. It is thus seen that when the sleeve 22 electrically connects the contact-feeler rods 70 that a circuit will 25 be closed and the electro-magnets 36 energized and the lever 31 drawn downwardly, lowering the pawl 25 so that it is positioned in the path of travel of the tooth 65 of the dog 61.

The operation of the apparatus is as follows: 30 While the filling is on the quill 21, the filling serves to cover the contact sleeve 22 and insulate it from the contact feeler rods 70, and hence the circuit to energize the electro-magnets is not closed when the lay moves forwardly to bring the 35 filling into engagement with the contact-feeler rods. The pawl 25 remains elevated, and is not engaged by the tooth 65 of the dog 61, which is continuously rocking transversely of the frame of the loom, during the operation of the loom. 40 When the last layer of the filling is removed from the quill, the contact sleeve 22 is thereby uncovered, and when the lay moves toward the contact-feeler rods 70, with the shuttle 20 at rest in the proper position, within limits, the contact-feeler rods 70 engage the contact sleeve 22 and a circuit is closed which will energize the electro-magnets 36. As soon as this occurs, the lever 45 45 is moved downwardly and the pawl depressed into the path of travel of the tooth 65 of the dog 60 61, and the forward swinging movement of this dog is transmitted to the filling feeler slide 23, which in turn swings the starting broad arm or lever 45 and turns the rock-shaft 46. This rock-shaft, through the medium of the connecting 50 means including the lever 48 will raise the latch or dog 16 so that it will be in the path of travel of the bunter 17, so that the action of the lay may operate the transerrer 14, as is well known in the art. An important feature of the invention is the fact that the contact-feeler rod 70 are placed relatively close together, and the contact sleeve 22 is relatively short, thereby preventing operation of the transerrer, if the shuttle 55 55 should stop a considerable distance outside 75

of a proper limit. If this should occur, only one contact-feeler rod 70 would engage the metallic contact sleeve 22, the other contact-feeler rod engaging with the quill, ordinarily formed of wood, and hence the circuit would not be closed 5 to energize electro-magnets, and the pawl 25 would not be lowered to be engaged by the tooth of the dog 61, for the purpose explained.

It is to be understood that the form of my 10 invention herewith shown and described is to be taken as a preferred example of the same and that various changes in the shape, size, and arrangement of parts may be resorted to, without departing from the spirit of my invention or 15 the scope of the subjoined claims.

Having thus described my invention, what I claim is:

1. In a filling replenishing loom of the bobbin-changing class having a transerrer dog, a 20 filling feeler slide having a forked end providing spaced tines, means to guide the filling feeler slide so that it reciprocates in a substantially horizontally rectilinear path, a rock-shaft which is continuously moved during the operation of 25 the doom, an upstanding cam follower dog mounted upon the rack-shaft and having an engaging part projecting between the tines, a bridge mounted upon the tines, a generally horizontal pawl arranged between and pivotally connected with the tines, a means connected with the bridge and with the pawl to hold it elevated out of the path of travel of said engaging part, a generally inverted U-shaped lever having a forked end straddling the bridge and pivotally connected with the bridge and its free end engaging the pawl, electrically operated means to 30 swing the lever toward the pawl for moving the same in to the path of travel of said engaging part, and means operated by the filling feeler 35 slide to actuate the transerrer dog of the loom.
2. In a filling replenishing loom of the bobbin-changing class having a transerrer dog, a filling feeler slide having a forked end providing spaced tines, means to guide the filling 40 feeler slide so that its reciprocates in a substantially horizontal rectilinear path, a reciprocatory 45
3. In a filling replenishing loom of the bobbin-changing class having a transerrer dog, a filling feeler slide having a forked end providing spaced tines, an upstanding cam follower dog moving during the operation of the loom, a second dog, a bolt carried by the cam follower dog and passing through an opening in the intermediate portion of the second dog, an adjusting bolt carried by the cam follower dog and engaging the second dog at a point remote from the first named bolt, the second dog being provided near its upper end with a pawl engaging part disposed between the tines, a pawl arranged between the tines and pivotally connected therewith, means to normally hold the pawl out of the path of travel of the pawl engaging part, an electrically operated device mounted upon the tines and adapted when energized to move the pawl downwardly into the path of travel of the pawl engaging part, a circuit adapted when closed to energize the electrically operated device and including a contact part mounted on the quill, and means operated by the filling feeler slide to actuate the transerrer dog of the loom.

45

SAINT JULIAN GEDDINGS.

cam follower dog operating during the operation of the loom and having an engaging part projecting between the tines, a generally horizontal pawl arranged between the tines and pivotally connected therewith, an inverted U-shaped bridge arranged above and connecting the tines, a means connecting the pawl and bridge to retain the pawl elevated and out of the path of travel of the engaging part, an inverted U-shaped lever having a forked end straddling the bridge and pivotally connected therewith and its free end engaging the pawl to move it downwardly, an armature carried by the lever, an electro-magnet arranged within the inverted U-shaped lever near and beneath the armature and mounted upon the bridge, a circuit adapted when closed to energize the electro-magnet including a contact element carried by the quill, and means operated by the filling feeler 20 slide to actuate the transerrer dog of the loom.

3. In a filling replenishing loom of the bobbin-changing class having a transerrer dog, a filling feeler slide having a forked end providing spaced tines, an upstanding cam follower dog moving during the operation of the loom, a second dog, a bolt carried by the cam follower dog and passing through an opening in the intermediate portion of the second dog, an adjusting bolt carried by the cam follower dog and engaging the second dog at a point remote from the first named bolt, the second dog being provided near its upper end with a pawl engaging part disposed between the tines, a pawl arranged between the tines and pivotally connected therewith, means to normally hold the pawl out of the path of travel of the pawl engaging part, an electrically operated device mounted upon the tines and adapted when energized to move the pawl downwardly into the path of travel of the pawl engaging part, a circuit adapted when closed to energize the electrically operated device and including a contact part mounted on the quill, and means operated by the filling feeler slide to actuate the transerrer dog of the loom.
